CLAIM

The ornamental design for a handle, as shown and described.

DESCRIPTION

FIG. 1 is a perspective view of the handle in accordance with a first embodiment of the present invention.

FIG. 2 is a top plan view of the handle of FIG. 1.

FIG. 3 is a bottom plan view of the handle of FIG. 1.

FIG. 4 is a right side elevational view of the handle of FIG. 1, the left side elevational view being a mirror reflection of the right side elevational view.

FIG. 5 is a front elevational view of the handle of FIG. 1.

FIG. 6 is a rear elevational view of the handle of FIG. 1.

FIG. 7 is a perspective view of the handle in accordance with a second embodiment of the present invention.

FIG. 8 is a top plan view of the handle of FIG. 7.

FIG. 9 is a bottom plan view of the handle of FIG. 7.

FIG. 10 is a right side elevational view of the handle of FIG. 7, the left side elevational view being a mirror reflection of the right side elevational view.

FIG. 11 is a front elevational view of the handle of FIG. 7; and,

FIG. 12 is a rear elevational view of the handle of FIG. 7.

FIGS. 2-6 and 8-12 are shown on a reduced scale.
